E. GOLDBACH.
LIFE PRESERVER.
APPLICATION FILED JUNE 19, 1915.

1,162,909.

Patented Dec. 7, 1915.

UNITED STATES PATENT OFFICE.

ERNST GOLDBACH, OF WINFIELD, NEW YORK.

LIFE-PRESERVER.

1,162,909.

Specification of Letters Patent.

Patented Dec. 7, 1915.

Application filed June 19, 1915. Serial No. 35,161.

To all whom it may concern:

Be it known that I, ERNST GOLDBACH, a citizen of the United States, residing at Winfield, Long Island, in the county of Queens and State of New York, have invented certain new and useful Improvements in Life-Preservers, of which the following is a specification, reference being had to the accompanying drawings.

10 This invention relates to certain improvements in life preservers, and it is an object of the invention to provide a novel and improved device of this general character which may be applied to the person with 15 convenience and facility and in such a manner as to in no way interfere with the movements of the limbs of the wearer.

Furthermore, it is an object of the invention to provide a novel and improved device of this general character comprising separable sections, each of which may be independently applied to the body and which, when required, may be suitably connected one with the other so that the best 25 results may be attained.

The invention consists in the details of construction and in the combination and arrangement of the several parts of my improved life preserver whereby certain important advantages are attained and the device is rendered simpler, less expensive and otherwise more convenient and advantageous for use, all as will be hereinafter more fully set forth.

30 The novel features of the invention will be carefully defined in the appended claims.

In order that my invention may be the better understood, I will now proceed to 40 describe the same with reference to the accompanying drawings, wherein—

Figure 1 is a view in perspective illustrating a life preserver constructed in accordance with an embodiment of my invention and arranged as if in applied position; Fig. 2 is a view in perspective of one of the members comprised in my improved device; Fig. 3 is an enlarged view, partly in end elevation and partly in section, of one of the members herein included; Fig. 4 is an enlarged fragmentary front elevation of one of the members as herein embodied; and Fig. 5 is a detail perspective view illustrating the adjustable connection between certain of the tabs herein employed.

As disclosed in the accompanying draw-

ings, 2 denotes a life preserver constructed in accordance with an embodiment of my invention and comprising a container formed of flexible material, said container being provided with a filling C of cork or other buoyant material which may be employed with equal facility. The walls of the container are preferably formed of two plies of material, the inner ply 1 being of suitable fabric and the outer ply 2 of rubber or other material impervious to water. The marginal portions of the container are provided with the bindings 3 also of woven fabric so that the stitching S employed for maintaining the same in assembled relation will not pull through the rubber or impervious layers 2. I also find it of advantage to connect the walls of the container with the longitudinally disposed parallel rows of stitching S' and in order to be assured of the best results, I find it of advantage to have the stitching S' disposed through the woven strips 4, for a purpose which is believed to be self-evident. I also find it of advantage 50 to provide the binding 3 and the strips 4 with a covering of rubber strips 5 secured thereto by a suitable adhesive. It is to be understood, however, that a liquid rubber or other water-proof composition may be employed 55 with equal facility. The preserver P, as hereinbefore described, is of such dimensions as to overlie the chest of the wearer but offering no obstruction whatever to the free movements of the arms and the upper 60 marginal portion of said preserver adjacent one corner is provided with the tab 6 provided with a snap hook 7 or the like adapted to be engaged by the eye members 8 carried by the stringer 9 secured to the upper 65 marginal portion of the preserver P adjacent its opposite edge.

In applying the preserver upon the person, the stringer 9 is disposed back of the neck whereby it will be perceived that the 70 preserver P is conveniently maintained in applied position and by the use of a plurality of eyes 8, it will be at once perceived that the position of the preserver upon the person may be adjusted with convenience 75 and facility as the requirements of practice may necessitate. In actual use, I have found that a single preserver may be employed with equal facility by adults and children and by persons of varying heights.

To further maintain the preserver upon the person, I secure to the opposite side mar-

ginal portions thereof the stringers 10 of such a length as to pass entirely about the trunk of the person so that the same may be suitably tied with convenience and facility at the front of the body.

In actual practice, I have found that a person able to swim may be readily sustained in the water by the use of a single preserver. However, in the event that a person is unable to swim, I find it of particular advantage to employ the additional preserver P' constructed in substantially the same manner as the preserver P, although preferably of greater dimensions. This additional preserver P' is adapted to overlie the back of the wearer and has its upper marginal portion provided with the tabs 11, each of which being provided with the snap hooks 12 or the like adapted for detachable engagement with the eye members 14 carried by the tabs 15 secured to the upper marginal portion of the preserver P. The tabs 11 and 14, when connected, are adapted to overlie the shoulders of the wearer and in order to maintain the preserver P' in applied position, I have secured to the side marginal portions thereof and in close proximity to its lower end, the stringers 16 adapted to be disposed around the body and suitably tied in front of the person.

Should the period of danger be unusually long and thereby requiring a person to have my improved life preserver in applied position, it will be perceived that the member or section P' can be used with convenience and facility as a head rest, in which event the stringers 16 are disconnected. This latter arrangement is particularly desirable for sea-faring persons, as it often occurs that parties engaged in this trade are compelled to remain upon the decks for a great length of time.

It will be at once appreciated that by having the walls of the members of the preserver comprising an inner layer of woven fabric 1 with the outer layer 2 of impervious material, the same are effectively protected against wear. If required, the detachable slip or cover 17 may be employed in connection with the members P and P' whereby the impervious layer 2 may be protected against wear as would otherwise possibly result when the sections are brought in contact with various obstructions. It is to be observed that the ends of the slips or casings 17 are open so that the retention of water therein which would otherwise have a tend-

ency to interfere with the convenient employment of my device, is eliminated.

From the foregoing description, it is thought to be obvious that a life preserver constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the scope of the appended claims and for this reason I do not wish to be understood as limiting myself to the precise arrangement and formation of the several parts herein shown in carrying out my invention in practice.

I claim:

1. A life preserver including a buoyant body, said body comprising a casing and a buoyant filler, the walls of said casing comprising a plurality of plies, the inner of said plies being woven and the outer of said plies being impervious, woven strips secured to the outer ply of the body and arranged in spaced relation, longitudinally disposed parallel rows of stitching engaged through said woven strips and connecting the walls of the casing, dividing the casing into integral sections.

2. A life preserver including a buoyant body, said body comprising a casing and a buoyant filler, the walls of said casing comprising a plurality of plies, the inner of said plies being woven and the outer of said plies being impervious, woven strips secured to the outer ply of the body and arranged in spaced relation, longitudinally disposed parallel rows of stitching engaged through said woven strips and connecting the walls of the casing, dividing the casing into integral sections, a tab secured to the upper margin of said body, a stringer secured to the upper margin of said body at the side opposite the tab, said stringer being adapted to be disposed around the neck of the wearer, coacting means carried by the stringer and tab whereby the same may be adjustably connected, and stringers secured to the side margins of the body adapted to encircle the waist of the wearer.

In testimony whereof I hereunto affix my signature in the presence of two witnesses.

ERNST GOLDBACH.

Witnesses:
